(57) **CLAIM**

The ornamental design for a clipper with applied surface ornamentation, as shown and described.

DESCRIPTION

This application makes reference to: U.S. utility application Ser. No. 14/193,367 filed Feb. 28, 2014. All disclosure and subject matter, including all figures, of the '367 application are specifically incorporated herein by reference in their entirety in this application as if set forth fully herein.

FIG. 1 is a front right perspective view of a clipper with applied surface ornamentation showing my new design;

FIG. 2 is a front elevation view thereof;

FIG. 3 is a rear elevation view thereof;

FIG. 4 is a left side elevational view thereof;

FIG. 5 is a right side elevational view thereof;

FIG. 6 is a top plan view thereof; and,

FIG. 7 is a bottom plan view thereof.

The evenly-spaced broken lines illustrate portions of the clipper and form no part of the claimed design. The dot-dash lines illustrate an unclaimed boundary line and form no part of the claimed design.
